(57) **CLAIM**

The ornamental design for a combined wireless network and power supply, as shown and described.

DESCRIPTION

FIG. 1 is a front, top and right side perspective view of a combined wireless network and power supply showing our new design;

FIG. 2 is a front elevational view of the combined wireless network and power supply;

FIG. 3 is a rear elevational view of the combined wireless network and power supply;

FIG. 4 is a top plan view of the combined wireless network and power supply;

FIG. 5 is a bottom plan view of the combined wireless network and power supply;

FIG. 6 is a left side elevational view of the combined wireless network and power supply;

FIG. 7 is a right side elevational view of the combined wireless network and power supply;

FIG. 8 is a front, top and right side perspective view of a first component of the combined wireless network and power supply;

FIG. 9 is a front elevational view of the first component of the combined wireless network and power supply;

FIG. 10 is a rear elevational view of the first component of the combined wireless network and power supply;

FIG. 11 is a top plan view of the first component of the combined wireless network and power supply;

(Continued)

FIG. 12 is a bottom plan view of the first component of the combined wireless network and power supply;
FIG. 13 is a left side elevational view of the first component of the combined wireless network and power supply;
FIG. 14 is a right side elevational view of the first component of the combined wireless network and power supply;
FIG. 15 is a rear, top and right side perspective view of the first component of the combined wireless network and power supply when it is in use;
FIG. 16 is a front, top and right side perspective view of a second component of the combined wireless network and power supply;
FIG. 17 is a front elevational view of the second component of the combined wireless network and power supply;
FIG. 18 is a rear elevational view of the second component of the combined wireless network and power supply;
FIG. 19 is a top plan view of the second component of the combined wireless network and power supply;
FIG. 20 is a bottom plan view of the second component of the two in one device combined wireless network and power supply;
FIG. 21 is a left side elevational view of the second component of the combined wireless network and power supply;
FIG. 22 is a right side elevational view of the second component of the combined wireless network and power supply; and,

FIG. 23 is a front, top and right side perspective view of the second component of the combined wireless network and power supply when it is in use.
